United States Patent Office.

HIRAM PRESTON, OF ORFORDVILLE, WISCONSIN.

Letters Patent No. 77,652, dated May 5, 1868.

IMPROVEMENT IN GAUGES FOR WEATHER-BOARDING.

The Schedule referred to in these Letters Patent and making part of the same.

TO WHOM IT MAY CONCERN:

Be it known that I, HIRAM PRESTON, of Orfordville, Rock county, in the State of Wisconsin, have made new and useful Improvements in "Gauges for Weather-Boarding;" and I hereby declare the following to be a full and exact description of the same, reference being had to the drawings that accompany and form a part of these specifications.

The object of my invention is to facilitate the operation of boarding or siding up buildings, and to do it with more accuracy than by the use of dividers and chalk-lines, formerly used.

Figure 1, perspective view.

Figure 2, side view.

Figure 3, showing application of gauge and scribe.

Letter A, crooked bar or shank.

Letter B, steel plate, attached to the lower part of the bar A, with spur or sharpened points *l* at the lower end, and the tongue *n* at the other.

Letter C, slide or rest.

Letter D, perpendicular scribe, attached to a sliding arm, *m*, supported in a groove, *t*, fig. 2, near the top of the bar A.

Letter *e*, thumb-screw, by which the slide C is held at any desired point.

Letter *f*, curved spring, to hold the board in place while being scribed or nailed.

Letter *h*, curved spring, which serves to hold the spur *l* more firmly in the wood by pressing against the board above.

Letter *i*, screw, by which the spur *l* may be adjusted, changing the angle of the plate B somewhat to suit the lumber being used.

The mode of operating will be readily seen. After your first board is in place, set the gauge by moving the slide C, so that the distance from the shoulder *k* to the top of the slide will be the width you desire from the edge of one board to that of the next. Then slip the tongue *n* under the lower edge of the last board nailed, bringing the shoulder close up to the edge of the board. The spur *l* will sustain it while the next board is placed above the slide. Then, by the application of the scribe D, which is at the very point needed, you have your guide for cutting the board at the angle desired.

To remove the gauge, press the top towards the building. This will relieve the spur from the wood, and it can be removed without scratching or marring the surface thereof.

By reference to the drawings, it will be seen that a slot is made in the arm to which the scribe D is attached, and the pin *p*, passing through the bar A and the slot, prevents its falling out of the groove. This pin can be removed, and the scribe also, when desired.

This device will be found very useful wherever boards are applied by being lapped on to each other, whether it be the small clapboards that are used over other boarding, or the larger, heavier boards frequently applied directly to the frame, and lapped one upon another.

What I claim as my invention, and desire to secure by Letters Patent, is—

1. The plate B, and screw *i*, as also the spring *h*, in combination with the bar A, substantially as described, and for the purposes set forth.
2. The scribe D, with the slotted arm *m* and pin *p*, constructed to operate in connection with the bar A, substantially as and for the purposes specified.

HIRAM PRESTON.
